UNITED STATES PATENT OFFICE.

ALBERTO I. WOODRING, OF WATERLOO, IOWA, ASSIGNOR TO NATIONAL SAFETY
DEVICES COMPANY, OF WATERLOO, IOWA.

OPERATING VALVE.

Application filed September 4, 1923. Serial No. 660,789.

To all whom it may concern:

Be it known that I, ALBERTO I. WOODRING, a citizen of the United States of America, and a resident of Waterloo, Black Hawk County, Iowa, have invented certain new and useful Improvements in Operating Valves, of which the following is a specification.

My invention relates to improvements in operating valves, and the object of my improvement is to supply a device of this class with valvular elements and means for releasably controlling them, adapted for occasional initial actuation in permitting the passage through the device to a receptacle of fluid under pressure and upon termination of such actuation to simultaneously cut off such fluid supply and to exhaust from the receptacle the residual fluid therein by way of the device.

The above object I have successfully accomplished by the means which are herein-after described and claimed, and which are illustrated in the accompanying drawing, the latter being a full size central vertical section of my device as separated from both its source of fluid supply and from a receptacle for such supply.

It is to be understood that changes in the precise embodiment of invention herein disclosed can be made within the scope of what is claimed without departing from the spirit of the invention.

Specifically, as shown, my device is designed and operable as means for controlling the supply of a fluid under pressure, such as compressed air, other gas, vapor or liquid, to a mechanism or a motor capable of utilizing the same for power or otherwise, as a receptacle containing a piston movable by fluid pressure thereagainst. After an actuation of said device to admit fluid under pressure to such a cylinder and the employment of the fluid in the latter to produce power movement of the piston, it is necessary to provide for the exhausting from the cylinder of the residual fluid, and this is effected by way of the passages of my device upon cessation of the action of the initially employed impulse upon the elements movably mounted therein.

The valve-chamber comprises the main body 1 having an upper chamber 23 and a lower chamber 24. A supply inlet passage 28 has a coned and threaded terminal part

30 for connection to a pipe or other conduit leading to a supply of air or other fluid under pressure and leads into the upper part of the chamber 24. A similar passage 27 has its outer end coned and threaded at 29 for connection to a conduit leading into a piston-containing cylinder or other device not shown for utilizing the power of the fluid under pressure which has traversed the valve-chamber from the lower part of the upper chamber 23. A horizontal septum separates the chambers 23 and 24 and contains a port or passage 25 which effects occasional communication between the chambers, the port being controlled by means of a cupped valve 8 in the chamber 24 whose hollow is fitted with an elastic annular packing ring 9 to engage the lower face of said septum tightly when the valve is in its elevated position. The valve-stem of said valve is interiorly threaded to receive adjustingly the depending threaded part 12 of a closure-body or head 11 which projects into the upper chamber 23, an integral quadrately widened and channelled part 10 fitting within the passage 25 to slide up and down therein.

The lower portion of the chamber 24 is interiorly threaded to receive a cupped plug 2 into whose hollow the lower end of the valve-stem may move downwardly freely, a coiled compression spring 13 being mounted around said valve-stem and engaged between the lower face of the valve 8 and the interior shoulder of the cupped plug 2. This spring normally retains the valve 8-9 upon its seat to close the passage 25.

The upper part of the body 1 is tapped with a concentric wider opening communicating with the chamber 23 and interiorly threaded to receive the exteriorly threaded lower part of a hollow plug 3. The lower part of the hollow of said plug is of slightly less diameter than the chamber 23, and the lower end of the plug engages a shoulder to effect a tight joint. The plugs 3 and 2, have respectively orificed ears 20 and 22, and 21, to receive screws or other fastening devices to affix the device to supporting-means. The upper part of the plug 3 is diminished cylindrically to receive a split clamping-body 7 thereon, said body having at its split a pair of lugs 18 orificed in line to receive a connecting and clamping-screw 19. The upper part of the body 7 is arched above the

upper end of the plug 3 and has at one angle a hole extending through it from front to rear to seat a pintle 17 secured by a split-pin. The arched top of the body 7 is also slotted or deeply grooved from one side to the other to receive a flattened end of an operating handled arm 14, this flattened part being pivotally mounted on the pintle 17 and having a cam-face 15 along its lower edge.

The numeral 4 denotes a reciprocatory plunger whose upper cylindrical and diminished head is fitted within the upper diminished hollow or bore of the plug 3 to project upwardly therefrom when raised. Upon this plunger is an integral annular shoulder which engages the shoulder at the junction of the upper and lower hollows of said plug 3. The lower part of the plunger is exteriorly-threaded to receive an interiorly-threaded sleeve 5, and a cupped leather gasket 6 is fitted upon the plunger and engaged between the upper end of the sleeve 5 and the lower face of said shoulder to elastically pack and effect a tight joint between the plunger and its incasing plug walls. The plunger is centrally longitudinally bored at 26 to open at its lower end, the upper end of the bore being closed, but a lateral port 16 being provided at 16 which opens to the atmosphere when the plunger is in its raised position, but is closed when the plunger is sufficiently lowered. The lower end of the bore 26 is conically widened to fit the upper end of the boss or part 11 below to close the bore at times.

The device is placed in operation by manually depressing the operating arm or lever 14 whose cam-edge 15 slides upon and pushes downwardly the plunger 4 closing the port 16. The lower end of the plunger engages the upper end of the body 11, closing the bore 26 at that end and also depressing the body 11 to open the valve 8-9 while compressing the spring 13. This allows compressed air to pass from the lower chamber 24 by way of the passage 25, the upper chamber 23 and the passage 27 to the communications leading to the power operated devices not shown. Work having been done in said communicating power-plant, the residual air is automatically exhausted therefrom, when the operating lever 14 is released. The spring 13 reacts to return the valve 8-9 to shut off the supply of air, while simultaneously the body 11 pushes up the plunger 4 part way. As the lower end of the plunger and also the gasket 6 are differentially of larger area than the contacting top of the body 11 the residual air in the chamber 23 still under pressure pushes up the plunger 4 still farther when the body 11 and valve 8-9 have arrived at their upper limit of travel, to leave the lower end of the bore 26 in com-

munication with said chamber 23 while the port 16 is open to the atmosphere, whereby such residual air is exhausted at once to the atmosphere.

My improved operating valve is applicable to many uses within the scope of the invention, as in the operation of signaling devices, brakes, or any other devices adapted to be controlled or actuated by a fluid under head.

Having described my invention, what I claim as new, and desire to secure by Letters Patent, is:

1. A device of the character described, comprising a valve casing having inlet and outlet ports, a resiliently-controlled valve in said casing to control the communication between said ports, said casing having a chamber communicating with the said ports by way of said valve, and said casing having a bearing aperture leading from said chamber, a reciprocatory body fitting said aperture and having a passage for occasional communication between said chamber and the atmosphere, and said body having its part which extends into said chamber of larger differential area than the said valve with its passage positioned for being closed by said valve at times when the body is moved to push the valve to an open position.

2. A device of the character described, comprising a valve casing having inlet and outlet ports, a resiliently-controlled valve in said casing to control the communication between said ports, said casing having a chamber communicating between the said ports by way of said valve, and said casing having a bearing aperture leading from said chamber, a reciprocatory body fitting said aperture and having a passage for occasional communication between the chamber and the atmosphere, said body having its inner part provided with an annular piston of greater differential area than that part of the valve contacted by the body when the latter is moved to contact with and push the valve to open position, and the passage in said body having its inner end closed by the valve contact while the upper end of the passage is closed by the casing, and means for moving said body to said valve-opening position while tensioning the resilient valve controlling means.

3. A device of the character described, comprising a valve casing having a chamber therein, inlet and outlet ports, and a valve-seat with a valve controlling its opening from the inlet port to said chamber, said outlet port opening into said chamber, and said casing having an apertured bearing, a body movable in said apertured bearing and having an exhaust-passage therethrough and movable against said

valve to open it, means for reactively returning the valve when released by said body, the passage in said body being closed by the valve while contacting therewith,
5 the body having an enlargement acted upon by residual fluid under pressure in said chamber when the valve is closed after actuation thereof by the body and release, to move the body out of contact of the valve,
10 exhausting the fluid in the chamber with- out the casing through said exhaust-passage, and a hand-lever mounted pivotally upon said casing having a cam thereon adapted to move the said body against the valve releasably when the lever is swung in one 15 direction.

Signed at Waterloo, Iowa, this 4th day of Aug. 1923.

ALBERTO I. WOODRING.
